UNITED STATES PATENT OFFICE.

WILLIAM BOSS, OF ST. PAUL, MINNESOTA.

HUMIDIFIER.

1,136,208.

Specification of Letters Patent. Patented Apr. 20, 1915.

Application filed February 21, 1914. Serial No. 820,353.

To all whom it may concern:

Be it known that I, WILLIAM BOSS, a citizen of the United States, residing at St. Paul, in the county of Ramsey and State of Minnesota, have invented certain new and useful Improvements in Humidifiers, of which the following is a specification.

My invention relates to humidifying devices to be used in connection with heating systems for residences or other buildings, particularly radiating systems employing steam or hot water and hot-air systems.

It is the object of my invention to provide a simple and efficient device for holding a supply of water and communicating said water to an evaporator, said evaporator being so positioned and related to other parts of the device that the currents of warm air generated from the heating system will be caused to pass over the surface of the evaporator, thus resulting in efficient and rapid evaporation for the purpose of conveying moisture to the air, thus relieving the condition of abnormal dryness which is so characteristic of rooms artificially heated and which is well recognized as productive of much ill health.

The full objects and advantages of my invention will appear in connection with the detailed description thereof and are particularly pointed out in the claims.

In the drawings, illustrating the application of my invention in one form, Figure 1 is a side elevation of my humidifier. Fig. 2 is a sectional elevation showing the humidifier in position at the back of an ordinary radiator. Fig. 3 is a top sectional plan view with some parts broken away. Fig. 4 is an end elevation. Fig. 5 is a fragmentary end section showing the manner of clamping the evaporator in position.

As illustrated, I provide a rectangular vessel 10, relatively narrow in proportion to its width and depth, adapted to receive a sufficient supply of water. Stamped outwardly in one or more series adjacent the top of the side walls are lip-like projections 11, which provide downwardly-turned mouths or openings 12. I have shown two series of such members 11 arranged in staggered relation along each side wall of the vessel 10.

Journaled in the end walls of the vessel 10 is a shaft 13, which may be of wire of the requisite thickness, arms 14, 15 being turned outwardly at right angles to the shaft 13

and preferably formed integrally therewith. Each of arms 14 and 15 is provided with a curved hook-like member 16 adapted to take over the connections 17 of a radiator 18 and suspend the vessel 10 along the side of said radiator between the radiator and the wire, as shown in Fig. 2. Where it is desired to use the device in connection with hot-air furnaces, it may be secured to the wall adjacent the register by means of a keeper 19, as indicated in Figs. 1 and 3.

Rigidly secured to the end walls of the vessel 10, preferably in the plane of shaft 13 which is at the centers of said walls, is a central handle or bail 20. This handle is provided with vertical portions 21 and a raised grip portion 22 at the center. Secured to the upper parts of the vertical portions is a bar 23, which serves as a support for the evaporating member 24. This evaporating member consists of a single strip of suitable fabric material, such as denim, doubled over the bar 23 and extending down into the vessel 10 to a point near the bottom thereof, as clearly shown in Fig. 2. The handle 20 is formed with depressed portions 25 near the ends thereof which normally engage the bar 23. The turned-over edges of the evaporator 24 are drawn between said depressed portions 25 and bar 23 and are thereby pinched and held in position, as indicated in Figs. 1 and 5. At the same time, the evaporating member 24 may readily be removed to be washed from time to time, which is desirable as any evaporating surfaces will necessarily be somewhat exposed and will accumulate dust.

The operation of the device is clearly indicated in Fig. 2. The water in the vessel 10 is carried by capillary action up the evaporating member. The currents of warm air from the radiator or register enter the openings 12 at each side of the evaporator 24, and in passing along the same withdraw moisture from said evaporating member and convey it into the atmosphere of the room.

The many advantages of this device will be obvious. It is compact, easily shipped and handled, is particularly convenient in household use, as the handle-grip 22 makes it easy to carry and place in position, and the hooks 16 being on a common shaft are always readily positioned. If the device is set within the keeper 19 for use in connection with hot-air furnaces, the hooks 16 may be eliminated. The evaporating member 24

can readily be changed whenever desired so that it will be unnecessary for the same to become seriously soiled or a breeding place for germs, as is true of evaporating members in which the wicking or evaporating member cannot be removed and washed. And the efficiency of this device is extremely high, due to the fact that the currents of warm air are thrown directly against the evaporating surfaces by reason of the openings 12 and the narrow shape of the vessel 10, and because of the wide extent of said evaporating surfaces.

I claim:

- 15 1. A humidifier for heating systems comprising a water container having side walls of relatively wide extent and an open top, an evaporating member extending between said walls and into the water in the container, means for removably holding the moisturizer in the currents of hot air generated by the heating system, and a series of downwardly-opening projections extending outwardly from said side walls into the 25 path of said warm-air currents for directing the same against said evaporating member.
2. A humidifier for heating systems comprising a water container having side walls of relatively wide extent and an open top, 30 a handle having end portions rigidly secured to the end walls of the container and a gripping portion extending above said open top,

a bar connected to said end portions and engaged by bends formed in the gripping portion, a fabric wicking removably held 35 upon said bar by said engaging bends so as to extend between said side walls and into the water of the container, and means for removably holding the moisturizer in the currents of hot air generated by the heating 40 system.

3. A humidifier for heating systems comprising a water container having side walls of relatively wide extent and an open top, a handle having end portions rigidly secured 45 to the end walls of the container and a gripping portion extending above said open top, a bar connected to said end portions and engaged by bends formed in the gripping portion, a fabric wicking removably held 50 upon said bar by said engaging bends so as to extend between said side walls and into the water of the container, a shaft journaled in the end walls of the container, and hooked arms rigidly connected with said shaft for 55 suspending said moisturizer from and back of a radiator of the heating system.

In testimony whereof I affix my signature in presence of two witnesses.

WILLIAM BOSS.
